Attorney

UNITED STATES PATENT OFFICE.

MOSES MORRIS, OF BALTIMORE, MARYLAND.

UNDERGARMENT.

Application filed October 19, 1926. Serial No. 142,682.

This invention relates to new and useful improvements in wearing apparel, and particularly to undergarments.

The principal object of the invention is to provide an undergarment of the closed seat type, wherein the required fullness is produced in the seat portion, of the back of the garment, without producing a fullness extending entirely across the seat portion of the back.

Another object is to provide a garment of this character in which the required fullness, in the seat, is produced by a novelly constructed insert, secured transversely within the back of the garment.

A further object is to provide an insert, for the back of a garment of this character, which provides for the simplest cut, in the back of the garment, to receive such insert, whereby to produce the desired fullness in the seat thereof.

A still further object is to provide a garment wherein the back is fulled over each buttock, thus producing a more perfect form-fit.

Heretofore, in making garments of this character, a single piece of goods was cut to the required length for the required fullness in the seat, which resulted in too great a length of legs, and side portions of the back, thereby necessitating the gathering up of the material, at the sides of the legs, to take up the excess of material, for the purpose of permitting the legs to hang in straight lines.

In the present invention, the back piece for the garment is cut to a length to produce the normal length of the legs, and by securing an insert in the goods, at the waistline, the intermediate portion of the back is permitted to drop sufficiently low to result in the desired fullness in the seat portion of the garment.

Other objects and advantages will be apparent from the following description when taken in connection with the accompanying drawings.

In the drawings:

Figure 1 is a rear elevation of a garment made in accordance with the present invention.

Figure 2 is a vertical longitudinal central sectional view, showing the fullness of the seat portion.

Figure 3 is a plan view of a modification of the insert, in the back of the garment.

Figure 4 is a plan view of the lower section of the back piece of the garment.

Figure 5 is a plan view of a further modification of the insert.

Figure 6 is a front elevation of the garment.

Figure 7 is a plan view of the crotch-piece.

Referring particularly to the accompanying drawing, it will be seen that the back of the garment comprises an upper section 10, a lower section 11, and an insert 13, the upper section being of the full width of the garment and extending down to the waistline, while the lower section 11 extends from the bottom of the insert to the lower ends of the legs 12.

As will be seen in Figure 5, the upper section 10 is formed with a straight transverse bottom edge, and that such edge is sewed to the upper edge of the insert 13, more particularly seen in Figure 1, said edge of the insert being straight, as shown. The lower section 11 is also formed with a straight transverse edge, but at its upper end. To produce these sections 10 and 11, the original piece of goods, which is to form the back of the garment, is cut transversely, on a straight line corresponding to the waistline of the finished garment. After having thus cut the goods to provide the sections 10 and 11, the section 11 is moved downwardly a sufficient distance, below the section 10, to provide a space to receive the insert 13.

It will be noted that the lower edge of the insert 13 is bowed, or curved, downwardly, in its intermediate portion, as shown at 13', and then curved upwardly, to a slight degree, toward its opposite ends, as shown at 14 and 15, so that the ends of the insert are approximately two-thirds of the width of the intermediate portion thereof. The upper straight edge of the lower section 11 is sewed to the lower edge of the insert, with the result that intermediate portion thereof will sag, or drop down, below the remaining or side portions, to produce the desired fullness in the seat of the garment, and yet retain the proper leg length without wasting the material by the usual gathering of the sides of the legs to cause such legs to hang in straight lines. In garments of this nature, now on the market, the lower edges of the legs incline upwardly from the inner sides to the outer sides. Were it not for

the downwardly extending end portions of the lower edge of the insert, the outer sides of the legs would be drawn upwardly to too great a degree, thereby producing an 5 inclination of the bottoms of the legs greater than that desired. The upwardly extending concave portions of the lower edge of the insert draw the material of the legs upwardly, but this is compensated for by the 10 downwardly extending convex portions at the ends of the insert, which permit the outer sides of the legs to sag or fall to the proper distance to produce the desired leg bottom inclinations.

15 The side edges of the section 10 are sewed to the upper portions of the sides of a front piece 16, while only one side edge of the lower section 11 is sewed to the side edge of the front piece. The other side edge of the 20 lower section 11, and the corresponding side edge of the front piece 16 are provided with suitable separable fastening means 17, whereby to produce a closure at the side of the garment, in one leg thereof, and a closed 25 seat portion. The lower edge of the bottom section 11, of the back of the garment is cut on an upwardly curving line 18, and to this edge is secured the rear portion of a substantially diamond-shaped crotch-piece 19, 30 shown particularly in Figure 7. The front piece 16 is slitted longitudinally and centrally from its bottom edge, as shown at 20, the side walls of such slit diverging upwardly, and being connected by a curved 35 bight portion 21. To the said side walls of the slit is sewed the other edge of the crotch-pieces 19.

In the form of the insert illustrated in Figure 3, the lower edge is cut in the same 40 manner as that shown in connection with the insert 13, of Figure 1, but the modification 22 has its upper edge formed in a similar manner to that of the lower edge, as shown

at 23. This provided for a fullness in the back, above the waistline, as well as there- 45 below.

The form of insert 24, shown in Figure 5, has its lower edge formed with two downwardly curved portions 25, with the intermediate portion upwardly curved, at 26, 50 and having the transverse ends 27. The downwardly curved portions 25, of the lower edge of this insert, when sewed to the upper edge of the lower section 11, of the back of the garment, produces fullness at 55 the two portions which cover the buttocks, as will be understood.

What is claimed is:

A garment including a back divided transversely along a straight line to produce an 60 upper section and a lower section, the upper section having a lower straight edge, the lower section having an upper straight edge, the lower section including leg portions, and an insert having its lower edge formed along 65 double compound curved lines to produce terminal and intermediate downwardly extending convex portions and upwardly extending concave portions between the terminal and intermediate convex portions, said 70 insert having its upper edge sewed to the lower straight edge of the upper section, the upper straight edge of the lower section being sewed to the compound curved lower edge of the insert, whereby such intermediate convex portion will permit the material of said lower section to sag in its intermediate portion, to produce a full seat portion to the back of the garment and whereby the terminal convex portions of said insert will 75 permit the outer sides of the legs to hang to the normal lengths downwardly from the hips.

In testimony whereof, I affix my signature.

MOSES MORRIS.
